Lipton, Weinberger & Husick(57) **CLAIM**

The ornamental design for a concealed-carry pocket, as shown and described.

DESCRIPTION

FIG. 1 is a front elevation view of the concealed-carry pocket of the invention installed on the inside of a garment, such as a vest, with one side of the garment open.

FIG. 2 is a back elevation view of the concealed-carry pocket viewed through the front of the vest with the vest closed and with a firearm in the concealed-carry pocket.

FIG. 3 is an enlarged front elevation view of the concealed-carry pocket as the pocket appears when viewed from the inside of the vest; and,

FIG. 4 is an enlarged back elevation view of the concealed-carry pocket as the pocket would appear from the outside of the garment with the front panel of the vest removed.

The broken lines shown in the drawings illustrate environmental structure and form no part of the claimed design.
